UNITED STATES PATENT OFFICE.

JAMES M. HALSTED, OF OAKLAND, CALIFORNIA.

TEMPERATURE-REGULATING DEVICE FOR INCUBATORS.

SPECIFICATION forming part of Letters Patent No. 352,053, dated November 2, 1886.

Application filed July 9, 1884. Serial No. 137,278. (No model.)

To all whom it may concern:

Be it known that I, JAMES M. HALSTED, of the city of Oakland, in the county of Alameda and State of California, have invented an Improvement in Devices for Regulating Temperature; and I hereby declare the following to be a full, clear, and exact description thereof.

My invention has special relation to regulating temperature in incubators, and is designed as an improvement on my former Letters Patent, Nos. 295,384 and 262,407.

The invention consists in the improved construction and combination of devices, as will be hereinafter more fully described with reference to the accompanying drawing, in which the single figure is a vertical section taken through an incubator, showing the application of my device to such an apparatus.

I have shown my device as applied to an incubator, in which A represents an incubator or egg-chamber, which may be of any suitable construction, and B is an air-chamber, made of metal or any material, fixed within the incubator. From this air-chamber, near one end, a tube extends downward through an opening in the floor of the egg-chamber, and far enough to dip into a cup, D, which is suspended below, as follows: A bracket, E, is secured beneath the floor of the egg-chamber, and the lever-arm F has its fulcrum within this bracket. The cup D is secured to this lever-arm at one side of the fulcrum, in a line beneath the tube C, and a weight, G, is secured at the opposite side at such a point that it will counterbalance the cup and the liquid contained within it. This liquid may be water or any other, but is preferably one which will not rapidly evaporate or be subject to other unfavorable changes. Glycerine fills these requirements very satisfactorily.

The arm of the lever to which the cup D is secured is connected with a means for increasing or decreasing the temperature. In the present case I have shown the rod H extending from the lever downward, and connecting with a lever or other mechanism by which the flame of the lamp I may be raised or lowered.

Upon the lever F is a small weight, J, which may be moved from the fulcrum toward the cup, if it is necessary to increase the weight; or it may be hung upon the opposite side of

the fulcrum, if it is necessary to counterbalance the weight of the cup.

The operation of this regulator will then be as follows: The air in the egg-chamber is heated to the desired degree, which in the present case is 103°, and the screw K, which controls the aperture in the air-chamber B, is put in tight. This closes the chamber, with the exception of the opening in the lower end of the tube C. The body of air within the air-chamber being of the same temperature as that outside and within the egg-chamber, if the temperature within the egg-chamber be increased a little, that within the air-chamber will be correspondingly increased, and the air will expand and force a portion of the fluid contained in the tube out into the cup. This makes the cup heavier than it was, and it sinks, carrying with it the end of the lever F, which, through the connection H, operates upon the lamp-wick, so as to reduce the flame, and this decreases the heat within the chamber. If the heat within the egg-chamber decreases, the temperature of the air-chamber has a corresponding diminution and contracts, thus drawing a portion of the fluid from the cup D upward into the tube C. This lightens the cup, and it rises, and, through the action of the lever, turns the heat on again, so continuing to move up and down, increasing or decreasing the heat within small limits as required. If it is desired to increase or decrease the heat a few degrees after the screw K has been fixed into its place, it may be done by the use of the small weight J. If the heat is to be decreased, this weight is hung on the lever between the fulcrum and the cup, its nearness to or distance from the fulcrum determining the amount of degrees. If, on the other hand, it is to be increased, the weight will be hung on the other side of the fulcrum, where the weight G is fixed. The action of this weight will be to compress or expand the air within the chamber, so as to retard or advance the rise and fall of the lever and cup, until the desired heat is secured. The air-chamber B has a partition, N, extending from the bottom upward far enough to prevent the liquid flowing back into the chamber from the pipe C, if it should ever be drawn up so high by the contraction of the air.

Having thus described my invention, what I claim as new, and desire to secure by Letters Patent, is—

As an improved means for regulating the temperature of incubators, the combination, with the stationary air-chamber B, located within the egg-chamber of an incubator, and a pipe, C, communicating with the air-chamber and extending from the same out through the incubator, of the liquid-containing cup D, located outside of the incubator, so that the liquid therein will not be influenced by the

heat of the incubator, the open outer end of the pipe C being immersed into the liquid of the said cup, a lever, F, connecting with the heat-controlling devices of the incubator, and secured to the cup, and counterbalancing weights on the lever for the cup, as set forth.

In witness whereof I have hereunto set my hand.

JAMES M. HALSTED.
